[57] CLAIM

The ornamental design for a wind wing, as shown and described.

DESCRIPTION

FIG. 1 is a front right side perspective view of a wind wing showing my new design with a vehicle and camper shell in broken lines for illustrative purposes only;

FIG. 2 is an enlarged outer side elevation view thereof;
FIG. 3 is a front end elevation view of FIG. 2;
FIG. 4 is an inner side elevation view of FIG. 2;
FIG. 5 is a rear elevation view of FIG. 4;
FIG. 6 is a top plan view of FIG. 2; and
FIG. 7 is a bottom plan view of FIG. 4.
